UNITED STATES PATENT OFFICE.

LOUIS ERNEST FRANCOIS FERRETTE, OF PARIS, FRANCE.

MINER'S SAFETY GLOWLAMP.

Application filed February 17, 1922. Serial No. 537,295.

To all whom it may concern:

Be it known that I, LOUIS ERNEST FRANCOIS FERRETTE, a citizen of the Republic of France, residing at 41 Rue Vital, Paris, France, have invented certain new and useful Improvements in Miners' Safety Glow-lamps, of which the following is a specification.

The present invention has reference to miners' safety lamps of the kind in which benzene, petrol or mineral oil is supplied through a vaporizer to a burner provided with a mantle for the production of an incandescent light, and in which means are also provided for varying the intensity of the light.

According to this invention, the lamp is provided with a locking arrangement adapted to positively prevent opening of the lamp when the latter is upright or suspended, but releasable when the lamp is turned over. Means may also be provided for closing the passage of the liquid illuminant so as to arrest the feed thereof to the burner and thus extinguish the light when the lamp is turned over. The locking arrangement referred to above may take the form of a stud movable within a tube or hollow bolt enclosing balls which, when the lamp is inverted, are adapted to pass from a lower to an upper chamber in the tube. When the balls are in the lower chamber, i. e., when the lamp is upright, they prevent upward movement of the said stud which is engaged at one end in a toothed rack. When, however, the balls are passed from the lower to the upper chamber, movement of the stud becomes possible and the latter can be released from the rack so as to permit the opening of the lamp. The means for closing the passage of the liquid illuminant may comprise upper and lower diaphragms fixed in a liquid reservoir, with a rod arranged between them. A ball may then be disposed on the upper diaphragm and arranged to close a passage leading to the burner when pressure is applied to the lower diaphragm.

A pump arranged in the liquid reservoir is adapted to supply air under pressure to the liquid illuminant or fuel contained in the reservoir so as to force said liquid into a smaller reservoir, from which it passes to a tube coiled at its upper part around the mantle. The liquid illuminant is vaporized

in the coiled part of the tube and passes from the said coils to the burner.

The pressure necessary to cause the liquid illuminant to flow is controlled by springs adapted to be adjusted prior to the closing of the lamp, thereby preventing any variation thereof while the lamp is closed. Furthermore, the air feed takes place through the lower part in a circuit protected by metallic wire-cloth screens. In connection with such lamp a so-called triplex glass cylinder is provided for surrounding the incandescent mantle.

By means of the improvements previously mentioned, the possibility of accidents or explosions is reduced to a minimum, the unscrewing of the lamp requiring time sufficient to insure the mantle and support becoming cool before the external air has access thereto.

One construction of lamp according to this invention is shown, by way of example, on the accompanying drawings wherein:—

Figure 1 is a longitudinal section of the lamp.

Fig. 2 is an enlarged detail view of the base of the lamp, and a rack thereon.

Fig. 3 is a plan view of the rack.

Fig. 4 is a section on line 4—4, Fig. 1, showing the air pump.

The same reference numerals indicated the same parts throughout the drawings.

Referring more particularly to the drawings, 1 is the main reservoir of the lamp, which is formed, by preference, of rolled and stamped sheet steel, and is tinned both inside and outside. 2 is a small auxiliary reservoir disposed vertically in the center of the main reservoir 1 and secured in place by a threaded plug or nut 3; said reservoir 2 being provided with an aperture in its base communicating with the reservoir 1. This reservoir 2 has for its object to insure, for a certain time, a feed of the liquid fuel, in the case of a lowering of the level thereof, due to the lamp being inclined, which would otherwise permit air to enter into the burner tube.

4 is a triplex glass or lamp glass cylinder, and 5 is an incandescent mantle.

6 and 7 are wire-cloth or gauze chimneys arranged to cool the flame in case of an explosion occurring in the lamp consequent upon the introduction of an explosive mixture; and 8 is a protective casing or shield

105

110

for preventing damage to the chimneys 6 and 7. On this shield 8 is riveted a cap 9 which supports a suspension ring 10. The lower end of the shield 8 is secured to a screw-threaded ring 13 which is detachably secured to an annular upper plate or ring 11, preferably of brass and disposed above the glass cylinder 4 on which it presses when it is secured to the base plate 12 of the lamp.

14 are metal rods or supports riveted at their upper ends to the upper plate 11 and at their lower ends to a flanged ring 15 overlying the base plate 12, which latter is provided with an air duct 68 and also with an upstanding, threaded annular collar 67 with which the ring 15 is directly connected. The duct 68 communicates with a ring or washer 66 supported on plate 12 and provided with gauze-covered openings to filter the air, as indicated in Fig. 1.

16 designates a tube or hollow bolt which is provided with a partition 22 dividing it into upper and lower compartments 26 and 28. A movable stud 17 is disposed within the tube and is adapted to engage the teeth of the rack 18 attached to plate 12. A spring 19 is mounted on the top of the stud 17, and bears at its upper end against the under side of a small plunger 20. Hard glass balls 21 are disposed within the tube 16, (Fig. 1), and are adapted to pass through an aperture 27 in the partition 22, which latter has both its faces hollowed out 35 to form opposite cones and is driven into the interior of the tube. A plug 23 is secured within the upper end of the tube 16, and a stud 24 is driven through the plate 11 into this plug so as to fasten the tube and plate together. The stud 17 is formed with a shoulder 25 adapted to rest on a counter-shoulder formed internally of the tube 16 so as to limit the downward movement of the stud. The lower chamber 28 in the tube 45 16, which is separated from the upper chamber 26 by the partition 22, contains the balls 21 when the lamp is in its normal upright position; but when the lamp is turned over, the balls will pass through the aperture 27 in said partition back into the upper chamber 26, as will be understood. The tube 16 is threaded at its lower end, as indicated at 50 29, and engaged in a threaded opening in the flanged ring 15, so that it can function as one of the supports 14.

30 and 31 designate capillary tubes, preferably of copper, which are connected at their upper ends by a coil 33 serving both as a support for the mantle 5 and as a heating chamber for the vaporization of the liquid fuel. The lower or inlet end of the tube 30 leads through the plug 3 into the safety reservoir 2, while the lower or outlet end of the tube 31 likewise passes through 60 said plug and opens into a chamber 32

therein, the chamber being closed at its bottom by a diaphragm 37. A tube 35 leads upwardly from the plug 3, to which its lower end is attached, and is provided at its upper end with a burner tip 34 located immediately below the mantle 5; said plug having an axial passage which constitutes an extension of the bore of the tube and which opens through a valve seat 36 disposed within said chamber. A hardened copper ball 38 is located within the chamber 32 for cooperation with the valve seat 36 and is normally disposed in a cup 39 also arranged in the chamber and secured to the diaphragm 37. A vertical rod 40, which passes axially through the reservoir 2 and is capable of endwise movement, is attached to the underside of the diaphragm directly below cup 39, and rests at its lower end on a second diaphragm 41, secured upon the bottom of reservoir 1 beneath reservoir 2. Movement of rod 40 is effected by means of an adjusting screw 71 which projects through the bottom of reservoir 1 and contacts with diaphragm 41 at a point in line with said rod. 90

The copper ball 38, by reason of its coaction with the seat 36, serves to regulate the passage through the burner tube 35 of the gases or vapors discharged into chamber 32 from tube 30, as will be understood. To this end, the position of the cup 39 wherein it is normally supported can be varied with relation to said seat by turning screw 71 in one or the other direction; and ball 38 can, if desired, be pressed into its seat, in which event, the supply of gas to the burner will be entirely shut off and the lamp, if lit, will be extinguished. This latter result will also be obtained automatically in case the lamp overturns, since the ball will thereupon fall 100 out of its cup into the valve seat and will be held tightly against the seat by the pressure.

Access to the main reservoir for filling purposes is effected by removing a plug 69 threaded into an opening in the plate 12, which plug can only be reached, however, by raising the glass cylinder 4—i. e., after the unit comprising the plates 11 and 15 and their connecting parts has been loosened. The initial filling level is indicated at 110 70 in Fig. 1.

In order to exert pressure upon the liquid fuel in the main reservoir 1, so as to force it into the auxiliary reservoir 2 and thence into the tubes 30 and 31, an air pump is provided which may comprise, as shown, a barrel 44 disposed within an outer protecting cylinder or casing 63, wherein it is held in place by a liner 64, and a piston 51 attached to one end of a hollow rod or stem 48 by means of a washer 52 and provided with a cup-shaped leather packing 45. The other end of the hollow rod 48 is provided with an operating button 47, and the bore of 120 130

said rod opens at opposite ends through this button and through the washer 52; a stuffing-box 50 being fitted in the outer end of the barrel 44.

5 An air-tight partition 55 is disposed in the inner portion of the barrel, and at opposite sides of this partition there are arranged an air delivery valve 49 and a safety valve 58 which are normally held in closed 10 position against their respective seats 56 and 57 by springs 53 and 59. The delivery valve 49 is provided with an extension or stem 60 which is adapted to be struck by the washer 52 on the pump piston, for the purpose 15 of opening the valve, as hereinafter explained; the space in front of said valve communicating with the space in front of the safety valve by way of a by-pass 61, and communicating through an opening 54 with the space between the barrel and the casing 20 63, which latter has an opening or port 62 providing communication with the interior of the reservoir 1.

In consequence of the above arrangement, 25 air will be drawn through the hollow rod 48 into the interior of the pump barrel 44 during the out-stroke of the piston 51; and if, at the end of this stroke, the opening in the button 47 is closed, as by the operator placing his finger thereover, the air thus retained in the barrel will be compressed when the piston is moved inward until the delivery valve 49 is opened by the piston striking thereagainst, whereupon the compressed air 30 will pass into the valve chamber, escaping therefrom through port 54 into the casing 63, and thence through port 62 into the interior of the reservoir 1. A certain amount of air flows through the by-pass 61 into the 35 safety-valve chamber during the compression stroke of the piston, but is returned therefrom and passes into the chamber containing the delivery valve when the latter is opened. The pumping operation thus serves 40 to supply compressed air to the interior of the reservoir 1, as will be understood, and is continued until the pressure in the reservoir is great enough to open the safety valve 58, whereupon the air will be free to escape 45 through the by-pass 61 into the pump barrel, and thence through the bore of the piston rod to the atmosphere.

No claims for the air pump and associated parts are made herein, but are included in a 50 separate divisional application, No. 676,154, filed November 21, 1923; claims for the extinguishing device per se are likewise omitted herefrom and form the subject of a second divisional application filed November 21, 1923, No. 676,155.

The operation is substantially as follows:—The main reservoir 1 is filled as above described, the plug 69 replaced and screw 71 adjusted to move ball 38 into position to close the end of the burner tube.

The air pump is next operated to place the fuel in the reservoir under pressure, and the connecting coil 33 which connects the tubes 30 and 31 and surrounds the upper end of the mantle 5 is then heated, whereafter 70 the screw 71 is turned backward just far enough to permit ball 38 to leave its seat and slightly open the gas passage. Priming can then be effected in a few moments, the supply being so regulated by means of screw 71 75 as to prevent the accumulation of excess gas around the mantle. The lamp is thereupon closed and all of the parts carefully arranged in position.

In tightening the parts, which is effected 80 by turning the threaded cap or ring 15 and its adjuncts, as explained above, the stud or detent 17 is displaced vertically with a reciprocating motion, due to its travel from tooth to tooth of the rack or ratchet 18, and 85 is gradually brought closer to said rack until it reaches a position where it cannot move backward a distance more than two or three millimeters, thus preventing the lamp from being opened unless it is overturned. During 90 this manipulation of the cap 15, the balls 21 pass from the upper chamber 26 in the tube 16 through the opening 27 in the partition 22 and pile up on top of the plunger 20 in the lower chamber 28, thus forming a 95 tight joint or abutment which prevents the plunger from moving but still permits a slight vertical movement of stud 17 in the initial stages of the rotation of the cap. During the last stages of rotation, however, 100 all vertical movement of the stud will be prevented, while backward rotation, which is essential for loosening the parts, will be checked by the stud end striking against the shoulder of the preceding tooth.

In order to open the lamp, it is necessary to first return the balls 21 to the upper chamber 26 in tube 16 so as to release the stud 17. This can only be done by inverting the lamp and striking one or two sharp blows against the tube in order to loosen the balls which will pass back into the upper chamber through the opening 27. During this operation, ball 38 closes the passage through tube 35, thus shutting off the supply of fuel to the burner and causing the lamp to become extinguished. Accidental explosion is thereby prevented, for the screwing of the cap and associated parts requires so much time that the mantle will have become cool before 110 the atmospheric air can obtain access thereto.

I claim as my invention:—

1. A safety lamp, comprising a reservoir for liquid fuel, a vaporizer, a burner, a feeding system between the two, a member separably related to the reservoir to permit the lamp to be opened and means adapted to positively prevent the separation of said member when the lamp is in upright position but rendered releasable when the lamp 125 130

is overturned; said means embodying a rack, a detent cooperative therewith, a tubular element wherein the detent is mounted, and balls for controlling the activity of the detent.

2. A safety lamp, according to claim 1, in which a spring-controlled plunger is associated with the detent, and in which there is a partition in the tubular element providing 10 upper and lower chambers, in the latter of which the plunger is arranged; said partition having an aperture for the passage of the balls one at a time therethrough into the lower chamber to form an abutment between 15 the partition and the plunger and thereby prevent the movement of said plunger and the detent.

3. A safety lamp, according to claim 1, in which the balls coat with a part carried by 20 the detent to lock the detent against disengagement from the rack.

4. A safety lamp, according to claim 1, in which the balls coat with two parts arranged within the tubular element to form a 25 joint between them and thereby lock the detent against disengagement from the rack, one of such parts being carried by the detent.

5. A safety lamp, comprising a reservoir for liquid fuel, a vaporizer, a burner, a feeding system between the two, a member separably related to the reservoir to permit the lamp to be opened, a rack rigidly related to the reservoir, a detent cooperative with the rack to prevent the separation of said member, and means for positively locking said 30 detent in engagement with said rack when the lamp is in upright position but rendered 35 releasable when the lamp is overturned.

6. A safety lamp, comprising a reservoir for liquid fuel, a burner, a feeding system therebetween, a member separably related to the reservoir to permit the lamp to be opened, a movable detent associated with the separable member, a locking member rigidly related to 40 said reservoir and cooperative with the detent to prevent the separation of the first-named member, and means for positively holding said detent in engagement with the locking member when the lamp is in upright 45 position but rendered releasable when the lamp is overturned.

In testimony whereof I affix my signature.

LOUIS ERNEST FRANÇOIS FERRETTE.
